SHOE

Basil Huff and Paul S. Birnbaum, Wilkes Barre, Pa., as signors to Faith Shoe Company, Wilkes Barre, Pa., a corporation of Pennsylvania

Filed July 25, 1962, Ser. No. 71,055

Term of patent 7 years

(Cl. D7—7)

FIG. 1 is a perspective view of a shoe showing our new design;

FIG. 2 is a view similar to FIGURE 1, viewing the same from the opposite position;

FIG. 3 is a top plan view thereof; and

FIG. 4 is a side elevational view thereof.

The characteristic feature of our design resides in the combination on the shoe disclosed of the specific contrasting insert at the front, which is shaped and serrated, as shown.

We claim:

The ornamental design for a shoe, as shown and described.
